HINGED BOX AND COVER DEVICE

Carl T. Osterberg, Milwaukee, Wis.

Application August 16, 1934, Serial No. 740,080

7 Claims. (Cl. 229—44)

My invention relates to a novel hinged box and cover device.

The object of my invention is to provide a box comprising a box receptacle and cover therefor with a hinge guard between the box receptacle and the cover, said hinge guard being so constructed as to limit the extent to which the cover may be hingedly lifted from the receptacle and so deformed upon a cover-closing operation as to assume such a position in full box-closed condition as to provide a resistance against a cover-opening motion.

Another object of my invention is to provide in a single unitary blank for the formation of a box cover structure means whereby the cover may be hingedly connected to the box receptacle and provided with a hinge guard.

In the drawing:

Figure 1 is a plan view of a box blank made in accord with my invention.

Figure 2 is an isometric view of a box formed from the blank shown in Fig. 1 and disclosed in cover-closed position.

Figure 3 is an isometric view of the box shown in Fig. 2 with the cover in open position and the hinge guard in position for a box-closing operation.

Figure 4 is a front elevation of the box shown in Figure 3 with the cover partially closed and the hinge guard in partially folded position.

Figure 5 is a perspective view of a box made in accord with my invention and shaped somewhat differently.

Like parts are identified by the same reference characters throughout the several views.

The box produced by my improved blank is preferably formed of fairly stiff cardboard or other suitable sheet material having characteristics which will permit of the resilient deformation of the hinge guard 50 which comprises probably the most important structural element pertaining to my invention.

In its major structural elements my box comprises a box receptacle 10 and a box cover 11 hingedly connected to the receptacle along one margin 12.

I have shown my improved box in Figs. 1 to 4 inclusive in the form of a box usable for matches, since the form thereof includes wide and narrow panels for sides and edges respectively of the box in a contrasting relation which facilitates the description herein, whereas the box shown in Fig. 5, likewise usable for old style matches for home use, illustrates the slight change in the configuration of the hinge mem-

bers 50 necessitated by the change in the general shape of the box.

The blank sheet of material shown in Fig. 1 is cut and scored as required for the formation of the box shown in Figs. 2, 3 and 4, and includes centrally disposed panels 13, 14, 15 and 16 respectively. The panel 13 may be referred to as a tab and comprises an extension of panel 14 which in the completed box forms the back of the box receptacle 10, the tab 13 being folded along a score line 17 at right-angles to the panel 14 to provide a reinforcement and connection with panels 18 and 19 which in superimposed relation form the bottom of the box receptacle. Tab 20 comprises an extension of panel 21 which, with panel 22, forms the double wall front of the receptacle in the completed box, and tab 20 in the completed box is folded at right-angles to panel 21 along the score line 23 so that the tab may extend along the bottom of the receptacle 20 and form a reinforcement therewith.

Panel 15 forms the top of the cover of the box and is connected with panel 14 along a score line 24 which comprises the hinged connection between the top or cover and the box receptacle 25 10. Wing panels 25 and 26 become the side panels of the cover of the box and are of identical dimensions with reinforcing wing panels 27 and 28 which, when folded in conjunction with the panel 16 which forms the front of the cover of 30 the box, may be swung along the score lines 29 and 30 to a position in which they are superimposed upon the panels 25 and 26 so that in the completed box as shown probably most clearly in Fig. 3, the sides of the cover of the box are dou- 35 ble in thickness.

It will be noted, as indicated, that the double lines at 31 and 32, between panels 25 and 27 on the one hand, and 26 and 28 on the other, represent a kerf which permits of the folding of the 40 panels so that 27 may overlay 25, and 28 may overlay 26 when the wing panels 27 and 28 are adjusted upon the score lines 29 and 30 and the panel 16 is adjusted upon score line 33 to its ultimate position with reference to panel 15 along 45 score line 33.

Panels 34 and 35 become side panels for the box receptacle 10 when they are adjusted upon score lines 36 and 37 which constitute the margin lines of the back panel 14.

From the above description of the blank as shown in Fig. 1, it will be apparent to those skilled in the art how the blank is adjusted to form the box shown in Figs. 2, 3 and 4. With the box formed in this manner the hinge guards 50 ex- 55

tending between score lines 38 and 39 are of such dimensions and so disposed that when the cover 11 is open, the hinge guard is substantially plane except for slight curvature induced by previous 5 bending operations as indicated clearly in said Fig. 3. When, however, as indicated in Fig. 4, the cover is in an intermediate position in a closing operation, the hinge guards 50 are forced to bend inwardly and they assume a position 10 within the confines of the cover 11 while the cover is in an intermediate position between full close and full open position.

Then, as the cover is moved downwardly upon the box receptacle 10, the guards unfold until in 15 full closed position they are fully extended once more, but this time in a position extending downwardly from the upper margins 39 of the box receptacle and, being in a confined relation to the side walls 25 and 26 of the cover 11 and side 20 walls 34 and 35 of the box receptacle 10, any attempt to open the cover once more is resisted by the hinge guards 50. It is only by brute force sufficient to distort the side walls of the cover and receptacle that it is possible to open the 25 cover once more, since in the folding and unfolding motion of the hinge guards 50 there must be additional room between the side walls of the cover and receptacle. Obviously, since the receptacle is usually filled or partially filled with 30 matches or other comparatively incompressible substances carried by the receptacle, it is largely distortion of the cover which permits the folding and unfolding of the hinge guards, and it will be noted that the side walls of the cover 11 are 35 double walls by reason of the coincidence of the panels 25 and 27 on the one side and 26 and 28 on the other.

In the formation of a box structure of shape differing from that shown in Figs. 1 to 4 inclusive, I may form my improved box as shown in 40 Fig. 5, in which the box receptacle instead of being cut away at 40, is substantially rectangular throughout and the hinge guards 51 extend forwardly at 52 to the front edge 41 of the box.

As a result of the construction shown in my 45 drawing in accord with my invention, it will be found that a box provided with hinge guards 50 or 51 will resist opening of my box and will also tend to hold the cover in substantially open position, and since the guards may be formed as 50 shown most clearly in Figs. 3 and 5, they are not in a position to interfere with the removal of the contents of the box receptacle.

I have found that the hinge guard 50 or 51 55 operates successfully partly by reason of the acute angular relationship of the top margin 39 of the box and the margin 38 of the cover. When the cover is in completely opened or completely closed position it thus means that the guard 50 provides an area such that it may be easily deformed within the dimensions of the cover and box.

I claim:

1. A box of paper-like material including a 60 body, a cover hinged to the body and provided with side walls, at least one of which is braced 65 against lateral movement, and a resilient side member of paper-like material connecting the cover and body and foldable to and from a position between the body and said braced wall of the cover in closing and opening the latter and operating through its resiliency to resist movement of the cover from open and closed positions.

2. A box of paper-like material including a

body, a cover hinged to the body and provided with side walls, at least one of which is braced against lateral movement, and a resilient side member of paper-like material connecting a body wall and said braced wall of the cover and foldable to and from a position between said walls in closing and opening the cover and operating through its resiliency to resist movement of the cover from open and closed positions. 5

3. A box of paper-like material including a 10 body, a cover hinged to the body at the back thereof and provided with connected front and side walls, and a resilient side member of paper-like material connecting the cover and the body and foldable to and from a position between the 15 body and a side wall of the cover in closing and opening the latter and operating through its resiliency to resist movement of the cover from open and closed positions.

4. A box of paper-like material including a 20 body, a cover hinged to the body at the back thereof and provided with connected front and side walls, and a resilient substantially triangular-shaped side member of paper-like material connecting the cover and the body and having a 25 spring bend disposed transversely of the box and intermediate of the member, said member being foldable to and from a position between the body and a side wall of the cover in closing and opening the latter and operating through its resiliency 30 to resist movement of the cover from open and closed positions.

5. A box formed from an integral blank and comprising a body, a cover hinged to the body along a rear margin thereof and provided with 35 side walls and a front wall connecting the side walls, and a resilient side member marginally joined to a body wall and a side wall of the cover and foldable to and from a position between said walls in closing and opening the latter and operating through its resiliency to resist movement 40 of the cover from open and closed positions.

6. A box formed from an integral blank and comprising a body having upstanding side walls and an upstanding rear wall permanently bonded 45 to the side walls, a cover having connected front and side walls and hinged to the body along its rear margin, and a hinge guard comprising a resilient foldable side member adapted to prevent excessive hinge movement and foldable in a 50 cover-closing operation to a position between a side wall of the cover and a side wall of the body, whereby to assume a plane position between said side walls and resistant to a cover-opening operation. 55

7. A box formed from an integral blank and comprising a walled body, a cover provided with side walls of double thickness and a front wall connecting the side walls, and a hinge guard integral with a side wall of the box and integral 60 with one thickness of a side wall of the cover, whereby to limit the hinged movement of the cover with respect to the body, said hinge guard being deformable in a box-closing operation, whereby to permit the side walls of the cover 65 to assume an overlying relationship to the side walls of the body, said hinge guard in the closing movement of said cover being received between side walls of the cover and body respectively, the double wall of the cover providing resistance to the deformation of the hinge guard 70 in a box-opening operation.

CARL T. OSTERBERG.
